UNITED STATES PATENT OFFICE.

PAUL E. HERRMANN, OF NEW YORK, N. Y.

HAIR-CURLER.

1,001,029.

Specification of Letters Patent. Patented Aug. 22, 1911.

Application filed January 3, 1911. Serial No. 600,441.

To all whom it may concern:

Be it known that I, PAUL E. HERRMANN, a subject of the German Emperor, residing at New York, in the county of New York 5 and State of New York, have invented certain new and useful Improvements in Hair-Curlers, of which the following is a specification.

The present invention relates to a curler 10 for a hair waving apparatus of the kind specified in my United States Letters Patent 959,527, issued May 31, 1910, and has for its object to provide a curler, which will allow of the curls being more easily attached and 15 securely held in position on the curler than by tying the ends of the curls as in the above named patent.

To make my invention more clear, the same is illustrated in the accompanying 20 drawing, in which similar reference letters denote corresponding parts and in which—

Figure 1 is a top plan view of the curler, the curls not being shown therein, Fig. 2 is 25 a side view thereof with the curls secured in position and Fig. 3 is a cross section on line 3—3 of Fig. 2.

The curler consists, as that in the above named patent, of a perforated hollow metal tube *a*. In one end, as at *b* of this tube a 30 spring member, *e. g.* a bifurcated pin *c*, or the like, is pivoted or otherwise rotatively secured, and at the opposite end the tube is provided with lateral oblong notches or slots *d* extending longitudinally of the tube.

35 A slide member *e* substantially of the shape shown in Fig. 3 and consisting of a piece of sheet metal, or the like, engages with its inwardly bent ends *e'* the slots *d*, while the curved upwardly extending portion thereof 40 forms a loop *e*² for the engagement of the

free end of the pin *c*. The width of the slots *d* is such as to allow play to the slide *e* in vertical direction. Consequently, when there is no curl wound around the tube *a* the pin *c* in engaging the slide, will permit 45 the latter to drop down to the extent of the width of the recesses or slots *d*. But after a curl *C* has been wound around the tube *a*, as indicated in Fig. 2, the pin *c* is swung to extend over said curl and in accordance with 50 the thickness of the curl will be pressed down more or less against its own spring force to cause it to engage the slide *e*. In thus engaging the slide, the pin will exert a certain pressure on the curl, securing it on 55 the tube *a* and at the same time draw the slide *e* upwardly, so that the latter by friction against the upper edges of the slots *d* will be prevented from an accidental displacement. Owing to the play allowed to 60 the slide within the slots *d* in vertical direction, the curler can be used for curls of various thicknesses.

What I claim and desire to secure by Letters Patent is:

A curler of the character described, comprising a perforated tube having lateral slots, a spring pin pivotally secured to one end thereof, a slide engaging said slots and capable of vertical displacement therein, 70 said slide being adapted to engage the said pin and hold the latter in position longitudinally over the tube.

In testimony whereof I affix my signature in presence of two witnesses.

PAUL E. HERRMANN.
